UNITED STATES PATENT OFFICE.

GARTH G. GILPIN, OF RIVERSIDE, ILLINOIS, ASSIGNOR TO P. H. MURPHY COMPANY, OF NEW KENSINGTON, PENNSYLVANIA, A CORPORATION OF PENNSYLVANIA.

FREIGHT-CAR ALL-METAL ROOF.

Application filed October 27, 1921. Serial No. 510,967.

This invention relates to improvements in freight car all metal roofs and more particularly to roofs of this character of the ventilated type such as described in my former Patent No. 1,300,258, of April 15, 1919.

Unless the metal surface on the underside of a roof of this character is covered with an insulation or lining it will sweat and the condensation drop down upon the lading.

10 The placing of a lining or insulation under the roof is an additional expense. However, this is obviated by arranging air ducts or ports along the edges of the roof which tend to equalize the temperature on both sides 15 and which will reduce or do away with the sweating. My former patent above referred to accomplishes this by striking up a rib adjacent each transverse edge of each roof sheet which ribs interlock to hold the roof sheets together and the edges at the side together with the upstanding ribs resting on the top of the car side plates, extended therebeyond and are bent down over the side sheathing which allows the passage of air 20 through the ribs but prevents water from entering or blowing into the interior of the car. It is an object of this invention to simplify the construction of a roof of this character and reduce the cost of fabrication by terminating each rib of the roof sheet just before the side edges are bent down over the car side plates and applying in lieu of the integral bent over rib a metal plate 25 pressed to correspond thereto which will continue the passageway to the ends of the side edges of the sheets.

While the preferred form of this invention is illustrated upon the accompanying sheets of drawings, yet it is to be understood that 30 minor detail changes may be made without departing from the scope thereof.

In the drawings:—

Fig. 1 is a perspective view of the top of a roof, with parts broken away, to which 45 a form of this invention has been applied.

Fig. 2 is an enlarged detail view in perspective illustrating the formation of the roof sheets before applying the improved ventilation cap.

50 Fig. 3 is an enlarged detail view in per-

spective of Fig. 2 illustrating one method of applying the ventilation cap.

Fig. 4 is a similar view illustrating another method.

Fig. 5 is a similar view illustrating the 55 application of a slightly different form of ventilation cap.

Fig. 6 is a similar view of a modified form of this invention.

Fig. 7 is a similar view of another modification.

As shown in the drawings the roof sheets extend transversely across the car and rest upon the side plates 1—1, the struck-up rib 2 of roof sheet 3 lays over and receives the 65 rib 4 of roof sheet 5 with the flange 6 of rib 2 resting on the body of sheet 5 and the corresponding flange of rib 4 lying under roof sheet 3. The bodies of the roof sheets are extended over the side plates and bent 70 down over the outside sheathing 7 of the car and may be attached thereto by bolts passing through both sheathing and side plate but the struck-up ribs 2 and 4 are terminated at the bend. To allow air to pass 75 through the ports or ducts formed by the struck-up ribs a ventilation cap is provided, preferably pressed from a metal plate, having a body 8 with a central struck-up rib 9 extending throughout of such dimensions 80 as to be received within the struck-up ribs of the roof sheets and to form an extension thereof to provide an air duct or port opening to the atmosphere at the edge of the roof sheets below the top of the side sheathing, 85 and with the top of both body and rib bent to rest on top of the side plate and against the exterior of the side sheathing of the car.

The ventilation cap 8 may be applied 90 under both roof sheets and rest upon the side plate, as shown in Fig. 3, and the bolts securing the roof sheet flanges may pass through the cap body or it may be inserted between the roof sheets, as shown in Fig. 95 4, or as shown in Fig. 5. The rib 10 of the cap may be of such dimensions as to lay over and embrace the outer roof sheet rib 2 with the body 11 extending to lay over the roof sheets and preferably tapered from 100

the bend at the top of the car side to the upper extremity of the rib 10.

The same idea is carried out in a roof in which the struck-up rib 12 of the roof sheet is reduced in height and tapered to merge into the margin of the roof sheet at the bend over the exterior of the car side, as shown in Fig. 6, and by gaining out the sheathing 7 directly under the end of the rib 12 and placing therein beneath and extending below the end of the roof sheet a ventilation cap 13 in the form of a plate having a depressed portion 14 fitted into the gained out sheathing which forms an air duct or port opening into the atmosphere below the roof sheet. Another method of accomplishing the same result in the latter type of roof is to secure spacing strips 15 to the top of the sheathing between said gained out portions and terminating the bottom of this portion on a line with the lower edges of the roof sheets, as shown in Fig. 7, and thereby forming a duct or port leading from the atmosphere from

below the edge of the roof to the interior of the car by the way of the interior of 25 the roof sheet ribs.

What I claim is:—

A ventilated car roof comprising metal roof sheets resting upon and bent down over the car side plates having transverse interlocking struck-up ribs between the bends of the roof sheets with the metal of each sheet extending in the same plane on the opposite sides of each rib adjacent to and on each side of each bend and the metal of each sheet 30 cut away from the end of each rib and the end of the sheet, closure plates each having a continuous struck-up rib adapted to be received within the interlocking ribs of each pair of adjacent roof sheets, said plates and struck-up ribs resting upon and bent down over the car side plate under said interlocking ribs and roof sheets with the plate rib 35 extending between the cut-away portions of the roof sheets adjacent their ends.

GARTH G. GILPIN.
